UNITED STATES PATENT OFFICE

THOMAS P. GARDNER, OF PORT ARTHUR, TEXAS, ASSIGNOR TO THE TEXAS COMPANY,
OF NEW YORK, N. Y., A CORPORATION OF DELAWARE

EJECTING MECHANISM

Application filed June 4, 1928. Serial No. 282,578.

This invention relates to improvements in spout making machinery and particularly to a device for removing or ejecting finished spouts from the dies on which they are formed.

The manufacture of spouts for assembly with can bodies in the making of liquid containers ordinarily involves the stamping of proper sized and shaped blanks from metal sheets and the subsequent formation of the spouts on dies or the like. The blanks are usually formed with opposed flanges on their side edges so that the flanges may be hooked together and then subjected to sufficient pressure to form a liquid tight seam. In machines adapted to form spouts in this manner, two operators are ordinarily required,—one to feed the preliminarily formed blanks to the holder dies, and another to remove the finished spouts from the dies.

My invention contemplates the provision of a device which is adapted to be used in connection with the usual spout forming machine. The object of the invention is to provide mechanical means for removing finished spouts from the dies on which they have been formed, thus doing away with the services of one of the operators ordinarily required.

Other objects, features and advantages of the invention will appear as the description thereof, in connection with the accompanying drawing, proceeds.

In the drawing, Figure 1 is a plan view of a portion of the spout forming machine with the mechanism embodying the present invention in position to cooperate therewith.

Figure 2 is an enlarged end view of the spout removing mechanism taken on the line 2—2 of Figure 1, portions having been broken away to better illustrate details of construction.

Figure 3 is an enlarged sectional view taken on the line 3—3 of Figure 1.

Referring to the drawing, 10 represents a vertically disposed rotatable shaft upon the upper end of which there is secured a hub or collar 11. A plurality of spaced and radially extending tapered rods or dies 12 are maintained in suitable sockets in the circumferential face of the collar, each die 12 being

adapted to receive a roughly shaped spout blank. Shaft 10 is rotated by power from any suitable source (not shown) and cam controlled means indicated generally at 13 are provided for intermittently checking the rotation of the shaft when successive dies reach the position of that indicated by reference character 12a, directly over a forming die 14. Forming die 14 constitutes one of a pair of dies which are adapted to close together around the roughly formed spout blank and to be subjected to sufficient pressure to press the blank into the desired form around the holder die 12a so as to press the hooked flanges together to form a liquid tight seam. Inasmuch as the spout forming mechanism forms no part of the present invention, a further description of the apparatus is unnecessary. The present invention relates to the auxiliary mechanism employed for the purpose of removing the finished spouts from the holder dies after the forming operation has been completed.

The spout removing mechanism or bumper, as it is commonly called, comprises a continuously rotating shaft 15 mounted in bearings 16, and having at one end a pulley 17 adapted to be rotated by a belt 18 which may lead to any suitable source of power. A gear wheel 19 is mounted on shaft 15 and meshes with a second gear wheel 20 which is secured on an idler shaft 21 mounted in bearings formed near the ends of a pair of spaced members 22 and 23 which constitute the arms of a bifurcated member 24. The body portion of the bifurcated member is formed with a bore so that it may be loosely mounted upon shaft 15 upon which it is free to move.

A friction wheel 25 is secured on idler shaft 21 between the ends of arms 22 and 23 of bifurcated member 24. Wheel 25 is formed with a peripheral groove 26 which may be lined or covered with rubber or any similar material. Bifurcated member 24 is formed with a link 27 to which any desired arrangement of connecting rods or the like, may be connected. The connecting rods are actuated by a treadle (not shown) operated by the operator in order that the position of friction wheel 25 may be under his control.

From the foregoing it will be seen that shaft 15 rotates continuously and in turn rotates gear wheels 19 and 20 and friction wheel 25 which is mounted on the same shaft 5 with gear wheel 20. By reason of the fact that bifurcated member 24 merely idles on shaft 15, and on account of the weight of the gear, friction wheel and shaft carried at the outer end of the arms, these members have 10 a tendency to move in an anti-clockwise direction as viewed in Figures 1 and 2. When the dies of the spout forming machine successively reach the position indicated by reference character 12c the formed spout 28 is 15 ready for removal. The operator steps on the treadle to actuate the connecting rods thereby producing a clockwise rotation of bifurcated member 24 which raises wheel 25 into frictional engagement with spout 28. The frictional resistance between the wheel and the spout is sufficient to loosen it on the outwardly tapering die 12c and to eject it therefrom.

Although it is considered preferable to 25 have the movement of the bifurcated member under the control of the operator who is feeding the roughly shaped spouts to the dies, it is obvious that cam controlled means might readily be substituted for the manually controlled means described.

A device of preferred form and construction has been illustrated and described for the purpose of showing a way in which this invention may be practiced but the inventive thought upon which this invention is 35 based is broader than the illustrative embodiment thereof and no limitations are intended other than those imposed by the appended claims.

40 What I claim is:

1. In an apparatus of the class described, a continuously rotating friction element adapted to engage a member formed on a die, means for rotating said friction element, and means for intermittently moving said friction element into engagement with the formed member under controllable pressures to release and eject the formed member from the die.
- 50 2. In an apparatus of the class described, a continuously rotating shaft, a bifurcated member idly mounted upon said shaft, a rotatable friction element mounted between the arms of said bifurcated member, means interconnecting said shaft and said friction element so that the friction element is continuously rotated in response to the rotation of the shaft, and means for actuating the rotating friction element into frictional engagement with a formed member to eject said member from the die upon which it has been formed.
- 55 3. In combination with a spout forming machine, a spout bumper comprising a rotatable driving shaft, means for continuously

rotating the shaft, a bifurcated member loosely mounted upon the shaft, an idler shaft journaled in openings in the arms of the bifurcated member, a friction element mounted on said idler shaft, a gear mounted upon each of the shafts, the gears meshing so that the friction element is rotated in response to the rotation of the driving shaft, and means for actuating the bifurcated member to move the friction element into ejecting engagement with a formed member to dislodge said formed member from the die upon which it is formed.

4. In an apparatus of the class described, a rotating friction member adapted to engage a member formed on a die, means for rotating said friction member, and manually operable means for moving said friction member into frictional engagement with the formed member under controllable pressures to release and eject the formed member from the die.

In witness whereof I have hereunto set my hand and seal this 22d day of May, 1928.

THOMAS P. GARDNER.
